CLAIM

The ornamental design for a display screen with animated graphical user interface, as shown and described.

DESCRIPTION

FIG. 1 is a front view of a display screen with animated graphical user interface, showing a first embodiment of my new design;

FIG. 2 is a second view thereof; and,

FIG. 3 is a third view thereof.

The appearance of the transitional image sequentially transitions between the images shown in FIGS. 1-3. The process or period in which one image transitions to another image forms no part of the claimed design.

The broken lines showing the display screen and elements of the graphical user interface illustrate portions of the article. No subject matter shown in broken lines forms part of the claimed design.
